Primary Examiner — Caron D Veynar*Assistant Examiner* — Abraham Bahta(74) Attorney, Agent, or Firm — Norton Rose Fulbright US LLPCLAIM

The ornamental design for a cap for cosmetic container, as shown and described.

DESCRIPTION

FIG. 1 is a top perspective view of the cap for cosmetic container showing my new design;

FIG. 2 is front view thereof;

FIG. 3 is a back view thereof;

FIG. 4 is a left side view thereof;

FIG. 5 is a right side view thereof; and,

FIG. 6 is a top view thereof.

The dashed lines in FIGS. 1-6 represent environmental structure and form no part of the claimed design. All other surface(s) or portion(s) of the claimed design in FIGS. 1-6 not shown in figures or otherwise described in the specification form no part of the claimed design.

1 Claim, 3 Drawing Sheets(56)
